(57) **CLAIM**

The ornamental design for a stabilizer jack pad, as shown and described.

DESCRIPTION

FIG. 1 is a bottom plan view of the stabilizer jack pad embodying our design;

FIG. 2 is a rear elevational view of our design; the front elevational view being a mirror image thereof;

FIG. 3 is a cross-sectional view of our design as seen along lines 3—3 of FIG. 1;

FIG. 4 is a left side elevational view of our design;

FIG. 5 is a top plan view of our design;

FIG. 6 is a right side elevational view of our design;

FIG. 7 is a bottom, front, right side perspective view of our design; and,

FIG. 8 is a top, rear, left side perspective view of our design.
